Primary Examiner — George D. Kirschbaum*Assistant Examiner* — Maria J Edwards*(74) Attorney, Agent, or Firm* — Brooks Kushman P.C.(57) **CLAIM**

The ornamental design for a shelf bracket, as shown and described.

DESCRIPTION

FIG. 1 is a perspective view of a shelf bracket showing our new design;

FIG. 2 is a front elevation view of the shelf bracket shown in FIG. 1;

FIG. 3 is a back elevation of the shelf bracket shown in FIG. 1;

FIG. 4 is a right elevation view of the shelf bracket shown in FIG. 1;

FIG. 5 is a left elevation view of the shelf bracket shown in FIG. 1;

FIG. 6 is a bottom plan view of the shelf bracket shown in FIG. 1; and,

FIG. 7 is a top plan view of the shelf bracket shown in FIG. 1.

In the drawings, the broken lines depict portions of the article and form no part of the claimed design.

1 Claim, 4 Drawing Sheets(56)
